UNITED STATES PATENT OFFICE.

LESLIE CARL DUTRO, OF POCATELLO, IDAHO, ASSIGNOR OF ONE-HALF TO WILLIAM A. ZETSCH, OF POCATELLO, IDAHO.

OIL-CUP.

1,162,586.

Specification of Letters Patent.

Patented Nov. 30, 1915.

Application filed September 2, 1914. Serial No. 3859,814.

To all whom it may concern:

Be it known that I, LESLIE C. DUTRO, a citizen of the United States, and a resident of Pocatello, in the county of Bannock and 5 State of Idaho, have invented certain new and useful Improvements in Oil-Cups, of which the following is a specification.

My invention relates to lubrication of bearings, and the main object thereof is to 10 provide an oil cup which will deliver oil to a bearing only at the time and in the degree of need; a further object is to provide means for adjusting the relationship between the need and the feed of the oil; and further 15 objects are to provide such oil cups which are simple in construction, positive in operation, well adapted to the purpose for which they are intended, and comparatively inexpensive.

20 My invention is fully described in the following specification, of which the accompanying drawings form a part, in which the separate parts are designated by the same reference characters in each of the views, 25 and in which:—

Figure 1 is an elevation of an oil cup constructed in accordance with my present invention; Fig. 2 is a central, vertical, section therethrough; and Fig. 3 is a plan view 30 thereof, with the cap removed.

In the drawings forming a part of this application I have shown an oil cup 4 having a removable cap or cover 5 mounted thereon in an air-tight manner, and a well 35 casing 6 screwed into the bottom thereof and held by means of a set-screw 7, said well casing having a centrally arranged tube 8 extending upwardly from the bottom thereof and the bore of which opens through said 40 bottom, as shown at 9.

In the form illustrated, the tube 8 is of a height approximating one-half the height of the well casing 6, and is internally screw-threaded to receive a supplemental tube 10 45 vertically adjustable therein, and it will be noted that the exterior of the well casing 6 is also screw-threaded for engagement with the housing of a journal, indicated by dotted lines in Figs. 1 and 2.

50 It must be understood that, when the cup is filled and the cover replaced, any air therein is at atmospheric pressure and, as nature abhors a vacuum, the oil 11 within the cup cannot pass through the tube 8 by reason of the fact that the cap 5 is air-tight; when the

bearing begins to heat, the temperature of the well casing 6 is raised correspondingly, thereby causing the oil in the cup to expand, if the cup be full of oil, or the oil and air if the cup be only partially filled, and this 60 expansion causes a portion of the oil to be forced through the tube 8 and to the point of use, the degree of which is determined by the degree of temperature of the well casing 65 and consequent expansion of the contents 65 of the cup, oil, or oil and air.

As soon as the bearing cools, the temperature of the well casing 6 falls, and the contents of the cup contracts, thereby stopping the feed of oil, and this contraction of the 70 cup's contents also draws in enough air to take the place of the oil which had been forced out of the cup, and the cup is ready for another operation.

Inasmuch as the well casing 6 is the first 75 to feel the changes in temperature, the oil therein is the first affected, and, if the tube 8 is of relatively small height, this oil will immediately feed to the bearings, and this might result in a too free feed; I therefore 80 provide the supplemental tube 10 which may be adjusted vertically in the tube 8 to alter the moment of feed, but, for ordinary purposes and with known qualities of oils, the height of the tube 8 may be fixed and the 85 tube 10 dispensed with.

As already stated, the air in the cup is not under atmospheric pressure; as a matter of fact, when not entirely filled with oil the air within the cup is slightly below atmospheric pressure due to the weight of the oil in the cup. The reason for regulating the length of the feed tube is to regulate the amount of oil in said feed tube, the longer the feed tube is the more oil will be 95 contained therein; now, say there is a rise of three or four degrees in the temperature of the bearings; this will cause a corresponding rise in temperature of the oil in the cup, thereby expanding said oil, let us say three 100 drops; instead of these three drops expansion causing a corresponding air pressure within the cup, these three drops of oil drop out of the feed tube on to the shaft, and this lessens the friction in the bearings, causing 105 the shaft to return to normal temperature; this causes the oil in the cup to contract, say three drops, and, if the feed tube holds ten drops, this will leave seven drops in the feed tube in the top part, and air will be in 110

the bottom part; if the temperature of the bearings again rises the same three or four degrees, there is the same expansion as before, but instead of the oil dropping from the tube to the shaft, it merely fills up the air-filled space in the bottom of the feed tube; the bearings will thus be compelled to rise several more degrees in temperature before there is any oil flowing on to the shaft, thereby causing a saving in oil.

My cup possesses the advantage of being highly sensitive to slight variations in temperature, thereby catching a bearing before it really starts to heat. It will be noted that there is a space surrounding the tubes 8 and 10, thereby enabling the heat of the bearing to reach the main body of the oil much more quickly and with a materially less rise in temperature.

It will be noted, from the above, that the oil in my cup is not forced from the cup by air admitted thereto under pressure, nor is it drawn therefrom by suction, nor does my cup extend to the shaft in the manner of some oil cups known to me.

Air is permitted to enter the oil cup through the tube 10 only in the degree of requirement, and the air in the cup serves as a cushion to insure the discharge of oil from my cup when required, regardless of the amount of oil in the cup, provided that it covers the upper end of the tube 10.

It will thus be seen that my oil cup is entirely automatic in action, all the attention it needs being to supply the same with oil, and no oil is wasted by seeping out of the cup or by running out of the journal bearing, and the moment of stop and start of feeding is under control by extending the tube 10 a greater or less distance into the body of the oil.

Reserving the right to make such changes in the form shown as come within the scope of the following claims, what I claim as new, and desire to secure by Letters Patent, is:—

An oil cup having an opening in the bottom thereof, a well casing fitted into said opening and provided with a central opening in the bottom thereof, a tube extended upwardly from said central casing opening to a point intermediate the height of said casing, a supplemental tube vertically adjustable in said first named tube, said central opening being of relatively small diameter and approximating the diameter of the bore of said supplemental tube.

In testimony whereof I have signed my name to this specification in the presence of two subscribing witnesses.

LESLIE CARL DUTRO.
